UNITED STATES PATENT OFFICE

JEAN TUFFÉRY, OF SEVRES, FRANCE

APPARATUS FOR RECONDITIONING SPORTING-CARTRIDGE CASES AND THE LIKE

Application filed May 10, 1927, Serial No. 190,172, and in France May 22, 1926.

Used sporting cartridges comprise each a fired case of which the external and internal surfaces have been expanded and distorted by the explosion of the powder and the open end 5 of which case has been more or less torn by the expulsion of the shot.

Various apparatuses have already been proposed for carrying out one or another operation requisite for the re-conditioning of fired 10 cartridge cases, but the use of such apparatuses entails numerous manipulations. In particular, it is necessary to transfer the cases successively from one apparatus to another, which involves a slow and inconvenient 15 process. Moreover some of said apparatuses necessitate several manipulations in order to effect a single operation.

The object of the present invention is to 20 avoid these drawbacks and to provide an apparatus enabling sporting cartridge cases to be re-conditioned in an easy and rapid manner, the case remaining in place in the apparatus during all the re-conditioning operations.

25 A preferred form of the invention is illustrated on the accompanying drawings in which:

Fig. 1 is a longitudinal axial section of the apparatus.

30 Figs. 2 and 3 are transverse sections of the apparatus respectively along the lines 2—2 and 3—3 of Fig. 1,

Fig. 4 is a horizontal section of the carriage along the line 4—4 of Fig. 3,

35 Figs. 5 and 6 are partial sections of the apparatus, one showing the initiation of the ejection of the detonated percussion cap, the other showing the initiation of the insertion of a new cap,

40 Fig. 7 is a section of the right hand portion of the apparatus acting as an upsetting tool,

Fig. 8 is a view showing the driving mechanism of the rotary mandrel.

The apparatus comprises a frame 1 in 45 which is provided a clamping screw 41 hav-

ing a clamping head 43; this arrangement enables the apparatus to be secured on a table, which is clamped between the head 43 and a fluted surface 47 formed beneath the frame.

Three groups of organs are removably 50 mounted on this frame: The re-conditioning organs (cap-ejecting, calibrating, smoothing, etc.), the organs for upsetting the re-conditioned and charged cartridge, and a central removable carriage between these 55 two groups of organs.

The re-conditioning organs comprise a calibrating socket 3, screwed in a sleeve 4, freely engaged by its web 3³ between two flanges of the frame 1; this socket rests by means of 60 machined surfaces 3² (Fig. 2) on the machined surface 1² of the frame 1 and is connected in a removable manner to the frame by screws 3¹.

A rotary mandrel 5 having a conical surface 12 is mounted in the sleeve 4 and journaled therein by a journal 6. A cap-ejecting nipple 13 having a neck 14 is mounted in a removable manner in the mandrel 5, this nipple being screwed in the end face 85 of the 70 mandrel 5.

A driving shaft 127¹, provided with a crank 9, operates the mandrel 5 through a train of spur gearing 127³, 5¹, (Fig. 8) in engagement with an intermediate wheel 128, 75 having a slot permitting it to be displaced on an intermediate spindle 128², for the purpose hereinafter explained. In order to be able to effect quick interchange of the mandrel 5 in accordance with the calibre of the cartridges, the spur wheel 5¹ is removably mounted on the end of the journal 6 of the mandrel 5.

The upsetting organs comprise a double 80 socket 125 providing a supporting bearing 85 at 99 and in which is screwed an upsetting socket 60. The journal 61² of an upsetting tool 61 turns in the bearing 99. This upsetting tool 61, constituted by a simple recess, is actuated in its rotary movements by 90

the train of gearing 61¹, 127⁴, the wheel 127⁴ being fixed on the end 127² of the driving shaft.

The double socket 125 presents a web 125¹ engaged between the flanges of the frame 1 and is removably connected to the frame e. g. by screws.

A removable abutment 18¹ having a thrust collar 97 is engaged by a centering plug 98 in the upsetting socket 60.

The carriage 19 consists of two elements, a socket 140 and a carriage body 141.

The socket 140 is formed as a nut and is screwed onto the threaded portion of the driving screw 127. It is of rectangular cross section (Fig. 3) which prevents it turning relative to the frame 1, whilst permitting it to slide on the frame. Two vertical guides 142¹, 142² are carried by the socket 140.

The body of the carriage 141 has a recess 37 for the engagement of the flange of the head of a sporting cartridge case when of the appropriate calibre, an aperture 25 for the ejection of the detonated cap and for the engagement of a new cap and a truncated conical seating 19³ to receive the flange of the sporting cartridge case during the upsetting.

The body of the carriage 141 has two vertical slides 143¹, 143² (Fig. 4) by means of which this body engages on the vertical guides 142¹, 142² of the guide socket 140.

This arrangement enables the instant removal of the body of the carriage body 141 and its replacement by another carriage body corresponding to the calibre of the cartridges which are to be operated on.

The socket 140 is engaged by a web 19¹ (Fig. 3) between the flanges of the frame 1 and rests by means of a machined surface 19² on the machined surface 1² of the frame, which ensures the proper guidance of the carriage during sliding.

The above described apparatus operates in the following manner. In order to recondition a used sporting cartridge 55 (Fig. 5), the flange 50 of the head of the cartridge case is engaged in the recess 37 of the carriage 19 (Fig. 5).

The crank 9 is then operated, turning the screw 127 in a direction so that the carriage 19 is displaced in the direction 130 (Fig. 1) relatively to the frame.

The paper tube 55, enters the free space left between the mandrel 5 and the socket 3 and is guided during this movement by the conical surface 12 of the mandrel 5.

The mandrel moreover is turned constantly about its axis by the gearing 127³, 128 and 5¹, and thus ensures the exact calibration of the sporting cartridge case 55 and the smoothing of the surfaces of such case.

At the termination of the above movement, the mechanism actuating the mandrel 5 is cut out by sliding the intermediate wheel 128 by means of its slot on the intermediate

spindle 128², which enables this wheel to be separated from the spur wheels 127³, 5¹. The rotation of the mandrel 5 is thus interrupted.

However, the carriage 19 continues its displacement in the direction 130 (Fig. 1), so that the detonated cap 56 encounters the ejecting nipple 13, (Fig. 5) the border of the cap engaging in the neck 14.

The cap 56 is thus ejected through the aperture 25 and drops outside the carriage 19. The rounded shape of the neck 14 prevents the expansion of the cap 56 during the preceding thrust and facilitates its extraction.

Moreover, there can be no fear of the upsetting of the wall of the cap 56, under the action of the mandrel 5, the mandrel being unclutched and ceasing all rotary movement, as has been explained above. For these various reasons the border of the cap 56 remains smooth. The cap is therefore easily ejected from the head 86.

At the termination of the preceding movement the head 86 comes to bear against the annular face 85 of the mandrel 5, which ensures the flattening of the head, after ejection of the cap 56.

A new cap can then be inserted into the cartridge. To effect this, the cap 60¹ is placed in the aperture 25 of the carriage 19, the cartridge 55, re-conditioned and dispossessed of its detonating cap, being mounted by means of its flange 56 in the recess 37 of the carriage (Fig. 5). The crank 9 is then actuated so as to displace the carriage 19 in the opposite direction i. e. reverse to arrow 130, the carriage body taking with it the cartridge 55 and the new cap 60¹. This cap therefore will encounter the abutment 18¹, which effects the insertion of the cap into the head 86, and the cartridge is thus capped.

The apparatus moreover avoids any error in capping, because if the cap 60 is not completely inserted in the head 86, it is impossible to disengage the cartridge from the carriage 19, owing to the cap remaining engaged in the aperture 25. In that case a renewed operation of inserting the cap is effected.

The re-capped sporting cartridge case is removed from the carriage 19 and is charged with powder and shot in the ordinary manner. It is then necessary to upset the cartridge case. To effect this, the cartridge is engaged by its flange in the truncated conical seating 19³ of the carriage, and the capping abutment 18¹ is removed from the upsetting socket 60, which thus becomes open ended (Fig. 7). The crank 9 is then turned in a direction so that the carriage 19 moves in a direction opposite to arrow 130. The cartridge case enters the upsetting socket 60. The upsetting tool 61 is at the same time rotated by means of the train of gearing 127⁴, 130

61¹ and thus effects the upsetting of the cartridge.

The above described apparatus ensures numerous advantages: Firstly it groups in a single machine all the organs necessary for the re-conditioning of sporting cartridges, which enables this work to be executed in a convenient and rapid manner, the used cartridge case remaining in the apparatus during the whole of this operation.

Moreover the re-conditioning organs (3, 5 . . .), the carriage 19 and the upsetting organs (60, 61 . . .) are mounted so as to be instantly removable. A sportsman can therefore use one and the same apparatus, employing several different sets of these organs, each set corresponding to a particular calibre of cartridge (12, 16, etc.); the same apparatus thus enables the re-conditioning of cartridges of various calibres.

It should also be noted that the re-conditioning organs, the carriage and upsetting organs being mounted on one and the same driving shaft, the actuation of the apparatus is effected by one hand, the other hand of the operator remaining constantly free.

Moreover the carriage 19 being mounted on the same shaft 127 as the re-conditioning and upsetting organs, such carriage is constantly centered with precision relative to those two organs.

The apparatus forming the subject of the invention can also be used for the calibration of deformed new cartridge cases. For this it suffices to mount the new and capped cartridge case in the carriage 19, to remove the uncapping nipple 13 from the mandrel 5 and to turn afresh such mandrel by means of the crank 9. Thus the calibration of the cartridge is effected, without risking any shock to the new cap, this cap being actually located opposite the aperture 25 of the carriage, and the nipple 13 of the mandrel 5 being removed.

I claim:

1. An apparatus for re-conditioning sporting cartridge cases and the like, comprising an organ for uncapping the cartridge case, an organ for re-capping said cartridge case, an organ for effecting the internal and external calibration of the cartridge case, a carriage located between said several organs and carrying the cartridge case, means producing displacements of said carriage so as to move the cartridge case successively into engagement with said several organs, and a single frame supporting all said organs.

2. An apparatus for re-conditioning sporting cartridge cases and the like, comprising an organ for uncapping the cartridge case, an abutment for re-capping said cartridge case, a calibrating mandrel, a central carriage located between said abutment and said mandrel, means for displacing said carriage so as to move it into engagement alternatively

with said abutment and said mandrel, and a frame supporting all said organs.

3. An apparatus for re-conditioning sporting cartridge cases and the like, comprising an organ for uncapping the cartridge case, 70 an organ for re-capping said cartridge case, an organ for ensuring the internal and external calibration of said cartridge case, an upsetting organ, a carriage located between said several organs, means for displacing said carriage, and a frame supporting all said organs. 75

4. An apparatus for re-conditioning sporting cartridge cases and the like, comprising an organ for uncapping the cartridge case, 80 an organ for ensuring the internal and external calibration of said cartridge case, an upsetting organ, an abutment removably mounted on said upsetting organ, so that a new cap can be inserted in said cartridge case 85 or said cartridge case can be upset.

5. An apparatus for re-conditioning sporting cartridge cases and the like, comprising an organ for uncapping the cartridge case, 90 an organ for re-capping said cartridge case, an organ for ensuring the internal and external calibration of said cartridge case, a driving shaft, means for causing said shaft to actuate alternatively said organs, and a frame supporting all said organs. 95

6. An apparatus for re-conditioning sporting cartridge cases and the like, comprising an organ for uncapping the cartridge case, an organ for re-capping said cartridge case, 100 an organ for ensuring the internal and external calibration of said cartridge case, a carriage located between said several organs, a driving shaft actuating said carriage, means for causing said shaft to actuate those of said organs with which said cartridge case 105 carried by said carriage comes into engagement, and a frame supporting all said organs.

7. An apparatus for re-conditioning sporting cartridge cases and the like, comprising an organ for uncapping the cartridge case, 110 an organ for re-capping said cartridge case, an organ for ensuring the internal and external calibration of said cartridge case, a screw-threaded driving shaft on which said carriage is mounted as a nut, means for causing said shaft to actuate those of said organs with which said cartridge case carried by said carriage comes into engagement, and a frame supporting all said organs. 115

8. In an apparatus for re-conditioning sporting cartridge cases and the like, the combination of an organ for uncapping the cartridge case, an organ for re-capping the same, a fixed sleeve, a calibrating mandrel rotatably mounted in said sleeve concentric therewith, means for rotating said mandrel about its axis, means for imparting to the cartridge case movements so as to cause it to engage between said sleeve and said mandrel to be cali- 120
125
130

brated and smoothed thereby, and a frame for supporting all said organs.

9. In an apparatus for re-conditioning sporting cartridge cases and the like, the combination of an organ for uncapping the cartridge case, an organ for re-capping the same, a fixed sleeve, a rotatable calibrating mandrel, means for rotating said mandrel about its axis, a nipple mounted on said mandrel and presenting a neck so that the border of the detonated cap becomes lodged in said neck thereby preventing the expansion of said cap and facilitating its extraction, and a frame supporting all said organs.

15. In testimony whereof I affix my signature.

JEAN TUFFÉRY.
